UNITED STATES PATENT OFFICE.

JULIANA WOOD, OF PHILADELPHIA, PENNSYLVANIA.

DESIGN FOR A BADGE.

SPECIFICATION forming part of **Design No. 23,235**, dated **May 1, 1894**.

Application filed **March 29, 1894**. Serial No. **505,644**. Term of patent **14 years**.

To all whom it may concern:

Be it known that I, JULIANA WOOD, a citizen of the United States, residing in the city and county of Philadelphia, State of Pennsylvania, have invented and produced a new and original Design for a Badge, of which the following is a specification, reference being had to the accompanying drawing, forming part thereof.

10 The leading feature of my design for a badge is the representation of the figure of a woman holding in one hand a plummet, and in the other a branch of a cedar tree.

In the drawing: A designates a badge on

the face of which is the representation of the figure of a woman B, in whose hands are held respectively the plummet C, and branch of a cedar tree D.

E and F designate rings which encircle said figure, and G designates a wreath of olive leaves which encircles the ring F.

What I claim is—

The design for a badge, substantially as shown and described.

JULIANA WOOD.
